UNITED STATES PATENT OFFICE.

DANIEL F. LEPLEY, OF CONNELLSVILLE, PENNSYLVANIA.

STOP MECHANISM FOR MINE-HOISTS.

1,216,143.

Specification of Letters Patent. Patented Feb. 13, 1917.

Application filed December 3, 1914. Serial No. 875,353.

To all whom it may concern:

Be it known that I, DANIEL F. LEPLEY, a citizen of the United States, residing at Connellsville, in the county of Fayette and State 5 of Pennsylvania, have invented a new and useful Stop Mechanism for Mine-Hoists, of which the following is a specification.

This invention relates to stop mechanisms for mine hoists.

10 Heretofore numerous accidents have occurred because the hoist engineer has overlooked the fact that the ascending cage contains miners and, consequently, the cage has been elevated above the ground level and 15 into the rigging above the mine with disastrous results.

One of the objects of the present invention is to provide means operated by a person at the bottom of the shaft prior to the 20 ascent of the cage, whereby the hoisting mechanism is set so as to prevent the elevation of the cage above the ground level. The mechanism constituting this supplemental stop is more especially designed as 25 an improvement upon the hoisting mechanism covered by my co-pending application filed September 28, 1914, Serial No. 863,972.

With the foregoing and other objects in view which will appear as the description 0 proceeds, the invention resides in the combination and arrangement of parts and in the details of construction hereinafter described and claimed, it being understood that changes in the precise embodiment of 5 the invention herein disclosed, can be made within the scope of what is claimed, without departing from the spirit of the invention.

In the accompanying drawings the preferred form of the invention has been shown.

10 In said drawings:—

Figure 1 is a side elevation of a mine hoisting machine with the present improvements combined therewith.

Fig. 2 is an enlarged view partly in side 45 elevation and partly in section of the attachment constituting the present invention, said attachment being shown in its set position.

Fig. 3 is a similar view showing the parts 50 when released.

Fig. 4 is a perspective view of the shift-able stop and its supporting lever.

Fig. 5 is a plan view of the structure shown in Fig. 2.

Fig. 6 is an end elevation of the mechanism.

Fig. 7 is a side elevation of a portion of the lever shifting rod and adjacent parts.

Fig. 8 is an end elevation of the rod shown in Fig. 7, the supplemental stop being indicated by dotted lines.

Referring to the figures by characters of reference 1 designates a shaft on which is mounted a winding drum 2 provided with a suitable brake indicated generally at 3 and 65 which brake can be operated by any suitable mechanism provided for that purpose, preferably mechanism such as shown in my co-pending application hereinbefore mentioned.

A chain 4 is actuated by the rotation of 70 shaft 1 and transmits motion through a sprocket 5 to a shaft 6 on which is secured a gear 7, this gear meshing with a gear 8 on the shaft 9 of which is secured a smaller gear 10. This gear meshes with a rack 11 75 to which rods 12 are pivotally connected, and on the rods are arranged opposed cushioning springs 13 and 14 bearing against adjustable collars 15 mounted on the rod.

A transverse shaft 16 is mounted above 80 the rod 12 and has a lever 17 extending therefrom provided, at its lower end, with a downwardly tapering eye 18. An arm 19 also extends from the shaft and is connected by a rod 20 to the brake controlling mechanism which is not shown in detail in the present case and constitutes no part of the present invention. Another lever 21 is mounted to swing on the shaft 16 and has a downwardly tapering eye similar to the eye 85 18, this lever being connected to a sleeve 22 from which depends an arm 23 having a rod 24 similar to rod 20 and which is connected to suitable mechanism for controlling the hoisting engine, this mechanism not being 90 shown in detail in the present case inasmuch as it constitutes no part of the present invention.

Extending into the tapering eyes at the lower ends of the levers 17 and 21 are trunnions extending inwardly from a forked lever 25 which is fulcrumed as at 26 and is pivotally connected, as at 27 to a rod 28 slidably mounted in a post 29. A weighted

latch 30 normally engages the rod for the purpose of holding it elevated and this latch is adapted to be actuated by a rod 31 connected to a bell crank lever 32 which, in turn, is actuated in properly timed relation with the ascent of the cage of the mine hoist by suitable mechanism indicated generally at 33 and which constitutes no part of the present invention.

10 Each of the levers 17 and 21 is provided, at its lower end, with a laterally projecting stud 34 swiveled thereon and provided with an eye 35 through which one of the rods 12 extends, this eye being interposed between the springs 13 and 14 on said rod.

15 All of the mechanism thus far described constitutes no part of the present invention, when considered by itself, but has been fully described and claimed in my co-pending 20 application hereinbefore referred to. It need only be stated that the parts of the mechanism are so proportioned that, during the upward movement of the cage due to the rotation of the winding drum 2, motion 25 is transmitted to the gear 10 and the rack 11 is shifted longitudinally so as to actuate the rods 12 and cause them to move slowly until one or the other of springs 13 and 14 comes against the eye 35 whereupon said 30 eye is shifted and the lever on which the eye is mounted is shifted gradually to its neutral position. When lever 17 is shifted to its intermediate or neutral position in this manner, it applies the brake 3 and, 35 when lever 21 is shifted to its intermediate or neutral position, it stops the engine used for operating the drum 2. Under ordinary conditions, this shifting of the levers 17 and 21 is designed to take place when the cage 40 reaches the upper limit of its movement. The present invention is designed primarily to bring the cage to a stop before it reaches said upper limit and, instead, as soon as it reaches the ground level so that if the 45 cage contains passengers, there will be no danger of their being carried upwardly to the superstructure. In order that this result may be attained, a wedging element or stop is used in connection with each 50 of the rods 12 so as to reduce the distance the rod must travel before either of the springs is brought into play and the lever is shifted and, consequently, so as to result in the shifting of the levers 17 and 21 and 55 the consequent application of the brake and stoppage of the engine before the cage reaches its uppermost position or, in other words, when the cage reaches the ground level. A forked lever 36 is fulcrumed on 60 a bracket 37 and has a weight 38 to facilitate its downward movement. Secured to each member 39 of the fork of said lever is a hanger 40 which increases in width toward its lower end and is provided with an 65 integral loop 41, there being longitudinal

slots 42 in the sides of the loop and within which the stud 34 is mounted to slide and rock. A rod 43 extends upwardly from lever 36 and is connected to an arm 44 extending from the lower end of a lever 45, 70 this lever being fulcrumed as at 46 and having a pawl 47 designed to be seated within a notch 48 in a segment 49 so as thus to hold the lever 45 against movement and support lever 46 and the hangers 40 in elevated 75 positions with the studs 34 in the lower portions of the slots 42. Pawl 47 has an arm 50 movable therewith and, when said pawl is seated in the notch 48, this arm overhangs a lifting rod 51 which is pivotally 80 connected, at 52, to a bell crank lever 53 and to a foot lever 54. A foot plate 55 is extended upwardly from end of the lever 45 while one arm of the bell crank lever 53 has an actuating cord 56 secured to it. This 85 cord extends down to the bottom of the shaft where it can be actuated by a person adjacent thereto.

It will be apparent that when lever 45 is locked in its intermediate position and the 90 hangers 40 are thus supported in their elevated positions, the rods 12 are capable of maximum movement and, consequently, the levers 17 and 21 will not be shifted to their neutral positions and the brake applied and the engine stopped, until the cage 95 operated by the hoisting mechanism has reached the uppermost limit of its movement. If, however, passengers are to be raised by means of the mechanism and are 100 to be landed at the ground level, one of the persons at the bottom of the shaft pulls upon the cord 56 and thus causes the bell crank lever to push upwardly upon the rod 51. This rod will lift the pawl 47 out of 105 notch 48 and the weight 38 on lever 36 will cause said lever 36 to swing downwardly, pulling through rod 43, upon lever 45 so as to shift said lever out of its intermediate position. When lever 36 moves 110 downwardly under the action of weight 38, the hangers 40 also move downwardly until the upper ends of the loops 41 are brought upon or close to the rods 12, thus holding the broadest portions of the hangers 115 between the two springs 13 and 14 on each rod. Consequently, less movement of the rods 12 will be necessary to bring the springs 13 or 14 into active positions and, by the time the ascending cage has reached 120 the ground level, one of the springs on each rod will have engaged the hanger 40 in the path thereof and, consequently, the two levers 17 and 21 will have been shifted to their neutral positions.

125 The manner in which the action of the levers 17 and 21 and the parts controlled thereby is advanced, can be readily seen by comparing Figs. 2 and 3. In Fig. 2 it is shown that when the hangers 40 are ele- 130

vated and the springs 13 are in one position, the levers 17 and 21 are only partly shifted toward their neutral positions. In Fig. 3, however, it will be seen that, when the hangers 40 are in their lowermost positions, the springs 13, even though in the same positions shown in Fig. 2, have moved sufficient distances to bring the levers 17 and 21 to their neutral positions.

10 What is claimed is:—

1. The combination with drums for winding cage supporting cables, a lever, and means operated by the lever for bringing the drums to a stop, of means operating in 15 timed relation with the drums for shifting the lever automatically to active or drum stopping position when a cage approaches a predetermined limit of its movement, and means under the control of a person at a low level of the cage, and independent of the operator, for instantly advancing the actuation of the lever into position to slow down and stop the drum ahead of the normal automatic movement of the lever by 20 said first mentioned means.

2. The combination with a drum for winding a cage supporting cable, drum rotating means, a lever, and means operated by the lever for stopping the drum rotating means, of means operating in timed relation with the drum for shifting the lever automatically to stop the drum when the cage approaches a predetermined limit of its movement, and means under the control of 25 a person at a low level of the cage, said means being independent of the operator, for instantly advancing the actuation of said lever into position to slow down and stop the drum ahead of the normal automatic movement of the lever by the lever shifting means.

3. The combination with a drum for winding a cage supporting cable, drum rotating means, a lever, and means operated by the lever to stop the drum rotating means, of means operating in timed relation with the drum for shifting the lever to stop the drum when the cage approaches a predetermined limit of its movement, a member 30 movably connected to the lever, means for supporting said member in inactive position, and means actuated by a person at a lower level of the cage and independently of the operator, for releasing said member thereby to instantly advance the actuation of the lever into position to slow down and stop the drum through the action of the lever shifting means.

4. The combination with a drum for winding a cage supporting cable, drum rotating means, a lever, and means operated by the lever for stopping the drum rotating means, of means operating in timed relation with the drum for shifting the lever to stop the drum when the cage approaches

a predetermined limit of its movement, a member slidably connected to the lever, means for locking said member in elevated position, means operated from a point remote from the lever and independently of the operator for releasing said member, and means for shifting the released member to position to instantly advance the actuation of the lever into drum stopping position ahead of the normal movement of the lever by its shifting means.

5. The combination with a drum for winding a cage supporting cable, a lever, and means operated by the lever for stopping the rotation of said drum when the cage reaches a predetermined position, of a rack, speed reducing means operating with the drum for actuating the rack, means operated by the rack for gradually shifting the lever to position to stop the drum during the movement of the cage to a limit of its movement, a member movably mounted adjacent the lever, means for locking said member in one position, and means operated at a point remote from the lever for releasing said member to position the member upon the rack actuated means, thereby to advance the actuation of the lever by said means.

6. The combination with a drum for winding a cage supporting cable, a lever, and means operated by the lever for stopping the rotation of the drum, of a rod slidably engaging the lever, speed reducing means operating in timed relation with the drum for shifting the rod, means upon the rod for engaging and actuating the lever to stop the drum, a member movably connected to the lever, means for locking said member in inactive position, and means operated at a point remote from the lever for releasing said member to advance the actuation of said lever by said means upon the rod.

7. The combination with a drum for winding a cage supporting cable, a lever, and means operated by the lever for stopping the rotation of the drum, of a rod slidably engaging the lever, speed reducing means operating with the drum for actuating the rod, spaced lever engaging means upon the rod, a member slidably mounted relative to the lever, means for locking said member in inactive position, means operated at a point remote from the lever for releasing said member, and means for shifting the released member into position between said means on the rod, thereby to advance the actuation of the lever by the rod.

8. The combination with a drum for winding a cage supporting cable, a lever, and means operated by the lever for stopping the rotation of the drum, of a rod, means operated in timed relation with the drum for actuating the rod, spaced means upon the rod for engaging the lever to shift

said lever and stop the drum when the cage reaches a predetermined position, a member slidably mounted relative to the lever, a lever connected thereto, a segment, a pawl engaging the segment, means held by the pawl for supporting the lever and member in inactive position, a pawl shifting element, flexible means for actuating said element to release the pawl and member, and means for shifting the released member into position

upon the lever engaging means on the rod, thereby to advance the actuation of the lever by the rod.

In testimony that I claim the foregoing as my own, I have hereto affixed my signature 15 in the presence of two witnesses.

DANIEL F. LEPLEY.
